C. C. MURPHY,

CAR ROOF.

APPLICATION FILED MAY 20, 1918.

1,277,246.

Patented Aug. 27, 1918.

Inventor:
Clinton C. Murphy,
by cause, his attorney.

UNITED STATES PATENT OFFICE.

CLINTON C. MURPHY, OF CHICAGO, ILLINOIS, ASSIGNOR TO P. H. MURPHY COMPANY,
OF PARNASSUS, PENNSYLVANIA, A CORPORATION OF PENNSYLVANIA.

CAR-ROOF.

1,277,246.

Specification of Letters Patent. Patented Aug. 27, 1918.

Application filed May 20, 1918. Serial No. 235,633.

To all whom it may concern:

Be it known that I, CLINTON C. MURPHY, a citizen of the United States, and a resident of the city of Chicago, county of Cook, and State of Illinois, have invented a new and useful Improvement in Car-Roofs, of which the following is a specification.

This invention relates to outside metal car roofs of the type wherein metal roof sheets extend from eaves to ridge and are movably secured to the substructure of the car.

The principal object of the invention is to provide a simple and inexpensive means for pivotally securing the roof sheets to the substructure, whereby the sheets can be replaced with little effort when worn or damaged.

The invention consists in an anchor member secured to the ridge portion of the car and provided with pivot holes adapted to receive the pivot members of a pair of opposite roof sheets. The invention further consists in the arrangements and combinations of parts hereinafter more clearly described and claimed.

In the accompanying drawing, wherein like numerals refer to like parts in the several views,

Figure 1 is a plan view of a portion of a car roof embodying my invention, the running boards being broken away to disclose the portion of the sheets located below;

Fig. 2 is a transverse cross-section on the line 2—2 in Fig. 1;

Fig. 3 is an enlarged cross-section taken through the ridge portion of the roof on the line 3—3 in Fig. 1;

Fig. 4 is a cross-section through the eaves portion of the car on the line 4—4 in Fig. 1 drawn to the same scale as Fig. 2, and

Fig. 5 is a cross-section through one of the transverse seams on the line 5—5 in Fig. 1, drawn to the same scale as Fig. 4.

In the drawings, the invention is shown applied to an ordinary type of car having roof sheathing boards 6 supported at both ends on side plates 7. Carlines 8 extend from side plate to side plate and support the ridge pole 9 and purlins 10, which members in turn support the roof sheathing boards 11 between the side plates. Side sheathing boards 11 and fascia boards 12 are secured to the side plates 7 beneath the ends of the roof sheathing, which projects out beyond the side face of the side plates and are flush with the outside face of the fascia.

Roof sheets 13 are arranged in pairs on opposite sides of the ridge pole and are provided at their eaves ends with doubled-under rebent flange portions 14. These flanges 14 are hooked under the rebent portion 15 of a continuous flashing strip 16, which lies in a rabbet formed in the eaves ends of the roof sheathing. The flashing strip is turned down over the eaves ends of the roof sheathing and is secured to the fascia boards by nails, or in any other desired manner. Each pair of roof sheets is spaced from the adjacent pairs and between the spaces thus formed along the sides of the sheets are battens or mullions 17. These battens are arranged transversely of the car extending from eaves to ridge on both sides of the car and are nailed or otherwise secured to the roof sheathing. The side and ridge margins of the sheets are flanged up at their edges and turned in and down, thus forming hooked portions 18 and 19. The side margins of the sheets are spaced from the battens and are covered by transverse seam covers 20. These seam covers are of inverted channel-shape in cross-section and have their lower side margins flanged inwardly and upwardly forming flanges 21 adapted to interlock with the hooked portion 18 formed in the side margins of each sheet.

The eaves ends of the transverse seam cover are held down at the eaves by eaves clips 22. The sheets are spaced apart at the ridge and are covered by ridge covers 23 similar to the transverse seam covers. The ridge covers straddle the marginal ridge edge of each adjacent pair of sheets and have flanges 24 similar to the flanges 21 of the transverse seam covers which interlock with the hooked portion 19 formed in the ridge end portion of the sheet. The ridge ends of the transverse seam covers 20 and both ends of the ridge covers 23 are secured in position by four-way corner caps 25, which are bolted to the roof substructure in the usual manner but permit limited movement of the sheets.

Running boards 26 are secured to the running board saddles 27, which rest on the corner caps 25 and the transverse seam covers 20, thus leaving the sheets free to move under the transverse and ridge seam covers.

Upstanding bosses 28 are formed in the roof sheets near their ridge ends, and are

arranged opposite each other on each side of the ridge cover. These bosses are provided with pivot pins 29 projecting upwardly therefrom. These pivot pins 29 are arranged centrally in the bosses and have reduced portions passing through the bosses which are riveted over on the underside to firmly secure them in position. An anchor member 30 is riveted or otherwise secured to the ridge cover transversely of the car midway between the transverse seams and in line with the bosses 28 of each pair of sheets. This anchor member 30 extends outwardly on each side of the ridge cover and is inclined downwardly so as to bring its end portion directly over and in close proximity to the respective bosses of each pair of roof sheets. The portions of the anchor member overlying the bosses are provided with holes 31 into which the pivot pins 29 of the roof sheets project and are thus pivoted therein. This arrangement permits the roof sheets to pivot or swing on the pivot pins of the roof sheets and thereby accommodate themselves to the weaving and racking of the car substructure. The anchor members, while serving as pivot bearings for a pair of roof sheets, also tend to hold the sheets in position on the roof sheathing.

The arrangement hereinbefore described is considered only as an example and as being the one most adapted to the type of roof shown. Therefore, I do not wish to be limited to the exact form of flexible seams or to the eaves construction shown, as the invention may be applied to roof sheets having various forms of flexible side and ridge seams.

40. What I claim as my invention is:

1. A car roof comprising a roof sheet, said roof sheet being movably mounted on the substructure of said car and having an upwardly extending pivot member, and an anchor member secured to car at the ridge, said anchor member having a perforated portion overhanging the pivot member of the roof sheet and adapted to be rotatably engaged by said pivot.

50. 2. In an outside car roof comprising roof sheets arranged transversely of the car, pivots secured to each of said sheets, and anchor members secured to the outside roof, each of said anchor members being adapted to receive the pivots of a number of sheets.

55. 3. In an outside car roof comprising roof

sheets arranged transversely of the car in pairs, pivots secured to each sheet of a pair, and an anchor member fixed to the outside roof, the pivots of each pair of sheets being adapted to rotatively engage said anchor member.

4. In an outside car roof, comprising roof sheets arranged transversely of the car in pairs, oppositely disposed pivot pins secured to each sheet of a pair near the ridge ends of said sheets, an anchor member secured to the outside roof, said anchor member being provided with holes adapted to receive the pivot pins of each pair of sheets.

5. In an outside car roof comprising roof sheets extending from the eaves to the ridge of the car, said sheets being arranged in pairs, the roof sheets of each pair being disposed on each side of the ridge, upwardly projecting pivot pins secured to each sheet in line transversely of the car, and an anchor member secured to the outside roof at the ridge, said anchor member being located above the roof sheets and having openings adapted to receive the upwardly projecting pivot pin of each pair of roof sheets.

6. In an outside car roof comprising roof sheets extending from the eaves to the ridge on each side of the car, ridge covers loosely connecting the ridge ends of said sheets, pivot pins secured to said sheets in transverse alignment, and anchor members secured to said ridge covers, each of said anchor members having openings in their end portions adapted to receive pivot pins of the adjacent sheets on each side of the ridge.

7. In an outside car roof comprising roof sheets extending from the eaves to the ridge of the roof and having their side margins loosely connected, ridge covers loosely connecting the ridge ends of said sheets, the eaves ends of said sheets being loosely secured to the car at their eaves ends and having upstanding bosses formed in the body portion near the ridge, upwardly projecting pivot pins secured to said bosses, an anchor member secured to the ridge cover, and arranged transversely of the car with its end bearing on the bosses of a sheet on each side of the ridge, the end portions of said anchor member having holes adapted to receive the pivot pin of a sheet on opposite sides of the roof.

Signed at Chicago this 14th day of May 1918.

CLINTON C. MURPHY.
